DOOR LOCK

Charles S. Bock, Chicago, Ill., assignor to Andrew Hoffman, Chicago, Ill.

Application January 12, 1940, Serial No. 313,623

8 Claims. (Cl. 292—346)

My invention relates to door locks, and particularly to those which are applicable to fire or emergency doors to enable them to be quickly opened for purposes of escape, and my main object is to provide a lock of this type which is proof to tampering or disabling influences.

A further object of the invention is to design the novel lock along lines to prevent jamming it by the insertion of pins, toothpicks or other articles having a wedging or blocking tendency.

Another object of the invention is to improve locks of the type contemplated with simple means to accomplish the intended purpose.

With the above objects in view and any others which may suggest themselves from the description to follow, a better understanding of the invention may be had by reference to the accompanying drawing, in which—

Fig. 1 is an elevation of the improved lock with its bolt projected;

Fig. 2 is an enlarged side view from the right of the showing in Fig. 1;

Fig. 3 is a section on the line 3—3 of Fig. 2, showing the bolt retracted;

Fig. 4 is a section on the line 4—4 of Fig. 3; and

Fig. 5 is a perspective view of the bolt.

Fire or emergency doors of the character mentioned above are usually employed in factories, schools and other buildings where a quick emergency exit is necessary or advisable. Thus, the lock for the door is applied to its inner side and carries a plunger or pedal usually marked "Push" and painted red, such plunger procuring the retraction of the bolt lock when actuated, and enabling the door to be pushed wide open. When the door is again closed, the bolt, being of the latch type, automatically snaps into locked position, and there is no way to open the door from the outside.

Obviously, it is the intention that a door of the above type be used for escape purposes only, and not for entrance purposes at any time. However, I have found that where the installation is used in schools the lock is tampered with after the door has opened for exit purposes, so that it will not lock when again closed. The usual method of tampering is to jam the bolt in the retracted position by means of inserting a pin, toothpick or other blocking article between the bolt and its bearing, so that the bolt will be inactive when the door assumes the closed position, enabling the door to be opened from the outside. It has therefore been my intention to so modify the construction of the lock as to prevent the

application of means to jam the bolt and so discourage the practice complained of.

In accordance with the foregoing, specific reference to the drawing indicates a typical emergency lock at 10, the same having a latch bolt 11 operating in one of its end faces 12. As indicated particularly in Fig. 3, the bolt 11 is of the generally triangular form and vertically pivoted at 13 in the housing of the lock. Also, the bolt is normally advanced or projected by a suitable spring mechanism 14, the particular character of this mechanism being of secondary importance in the present instance, since it suffices that the bolt should be projected to the position indicated in Figs. 1 and 2 and retractable to the position shown in Figs. 3 and 4. As contemplated, the bolt is retracted by pressure on a frontal push plate 15 which is pivoted at 16 to the lock housing, the means for accomplishing this being of any suitable type.

One feature of the present invention lies in the zone of the outer wall 16 along the inner side of which the bolt describes its arcuate travel. In the conventional lock, the said wall is fairly close to the periphery of the bolt, and it is in the tiny space there located that the pin, toothpick or other jamming article is inserted or wedged as the bolt is held in the retracted position. In order to prevent jamming of the lock in this manner, I have cut away the wall 16 from the front a short distance, as indicated at 17; also, the wall is located more distantly from the periphery of the bolt 11. The stock of the housing at points above and below the bolt is then perforated as indicated at 18 to journal the spindle 19 of a vertical roller 20 in a manner to place the roller in contact with the periphery of the bolt. Also, the roller is flush with the corner of the housing, as indicated in Fig. 3, so as not to project therefrom.

I have also altered the zone in the top and bottom closures of the bolt with the housing. Thus, the conventional lock shows a slight clearance space above and below the bolt in respect to the said entrance, and either of these spaces has been employed by tamperers to jam the bolt in the retracted position. I have found that where the extent to which the insertion of a pin or toothpick may be possible is very short, the power of the spring behind the bolt will advance the same despite the impediment and dislodge the same. To accomplish this, I have cut the bolt down from its top and bottom a short distance to appear as at 21, so that the outer wall 22 of the bolt presents upward and down-

ward flanges 23. The entrance to the housing is cut with angle receptacles 24 at the top and bottom of the bolt entrance, so that when the bolt closes, its top and bottom flanges 23 will seat in the receptacles as clearly shown in Fig. 4. Thus, if any slight spaces or cracks occur between the top or bottom of the bolt and the housing entrance, the insertion of any sharp article or obstruction will soon meet the back or seat of the corresponding receptacle 24 and be prevented from further progress. The short hold on the bolt thus gained will be insufficient to hold it against the urge of the internal spring, and the bolt will emerge despite the interference.

It will be apparent that the two features just described will counteract attempts to jam the bolt and soon discourage the same. In the first instance, it will be realized that the roller 29 can form an actual contact with the bolt periphery without in any manner resisting the action or freedom of the bolt to emerge from the housing, since the roller will also act freely in the manner of a roller bearing. This is in contrast with the possibility of building the wall 16 so close to the periphery of the bolt as to leave no space for the insertion of an obstructing article, in which event friction between the bolt and the housing would soon develop, defeating the intent of the present invention. With the bolt and roller sturdily designed and closely fitted, it will be impossible to insert an obstructing instrument by hand or to make it stay in place against the urge of the bolt to advance. As to the second feature, it stands to reason that a slight clearance space between the top and bottom of the bolt flanges 23 with the housing will be practicable, since it will furnish no appreciable hold or pocket for an obstruction.

A bolt improved along the lines described above will limit the function of the fire or emergency door to the prescribed use or requirements and discourage if not entirely eliminate attempts to tamper with the lock.

While I have described the invention along specific lines, various minor changes and refinements may be made without departing from its principle, and I desire to consider all such changes and refinements as coming within the scope and spirit of the appended claims.

I claim:

1. In a lock having a pivoted latch bolt formed with an arcuate periphery; movable means carried by the lock in contact with said periphery 55

and forming a closure between the bolt and the adjacent portion of its housing to prevent the insertion between said means and periphery of an instrument calculated to jam the bolt.

5. In a lock carried by the closing end of a door and having a vertically-pivoted latch bolt formed with an arcuate periphery; movable means carried by the door in contact with the full height of said periphery and forming a closure between the bolt and the adjacent portion of its housing to prevent the insertion between said means and periphery of an instrument calculated to jam the bolt.

15. In a lock carried by the closing end of a door and having a vertically-pivoted latch bolt formed with an arcuate periphery; movable means carried by the door alongside said periphery and in rolling contact with the same to prevent the insertion between said means and periphery of an instrument calculated to jam the bolt.

25. In a lock carried by the closing end of a door and having a vertically-pivoted latch bolt formed with an arcuate periphery; free-rolling means carried by the door in rolling contact with said periphery to prevent the insertion between said means and periphery of an instrument calculated to jam the bolt.

3. In a lock carried by the closing end of a door and having a vertically-pivoted latch bolt formed with an arcuate periphery; a vertical roller freely journaled in the bolt housing alongside the bolt and in rolling contact with said periphery.

4. In a lock carried by the closing end of a door and having a vertically-pivoted latch bolt formed with an arcuate periphery; a vertical roller freely journaled in the bolt housing alongside the bolt and in rolling contact with said periphery, the roller extending at least the full height of said periphery.

40. 6. In a lock carried by the closing end of a door and having a vertically-pivoted latch bolt formed with an arcuate periphery; a vertical roller freely journaled in the bolt housing alongside the bolt and in rolling contact with said periphery, the roller extending at least the full height of said periphery.

7. In a lock carried by the closing end of a door and having a vertically-pivoted latch bolt formed with an arcuate periphery; means between said periphery and the bolt housing preventing the insertion of an instrument calculated to jam the bolt.

45. 8. In a lock including a pivoted bolt having an arcuate peripheral surface; free rolling means carried by said lock in constant contact with said surface to prevent the insertion between said means and said surface of an instrument for jamming the bolt.

CHARLES S. BOCK.
